Henry W. Hensel, of Philadelphia, Pa.
Letters Patent No. 1797 - Dated July 7th 1863.

The schedule referred to in these Letters Patent and making part of the same.

To all whom it may concern:

Be it known that I, Henry W. Hensel, of Philadelphia, County of Philadelphia, State of Pennsylvania, have invented or produced a new and original design for "Blind Binding"; and I do hereby declare the accompanying drawing, with the following explanation of the same, to form a full, clear and exact description of the said design.

Each edge of the binding is ornamented by a border consisting of the chain represented in the drawing.

Between the borders the binding is ornamented by the two patterns A and B, arranged alternately, the pattern A, being of an oval form and the pattern B, of the diamond shape represented.

Pattern and design to secure
by Letters Patent. -

The ornamental figures and forms represented in and by the accompanying drawing, the whole forming a design for blind binding.

In testimony whereof I have signed my name to this specification in the presence of two subscribing witnesses,
